DESIGN FOR A FILING CABINET

Theo G. Ward, Los Angeles, Calif., assignor to Penday, Inc., Los Angeles, Calif., a corporation of California

Application March 31, 1947, Serial No. 138,071

Term of patent 7 years

(Cl. D33—19)

To all whom it may concern:

Be it known that I, Theo G. Ward, a citizen of the United States, residing at Los Angeles, in the county of Los Angeles and State of California, have invented a new, original, and ornamental Design for a Filing Cabinet, of which the following is a specification, reference being had to the accompanying drawings, forming part thereof.

Fig. 1 is a perspective view of a filing cabinet in the closed position, showing my new design; and

Fig. 2 is a perspective view of said cabinet in the open position, said view being taken from the side of the device opposite that of Fig. 1.

I claim:

The ornamental design for a filing cabinet, as shown.

THEO G. WARD.
